UNITED STATES PATENT OFFICE.

JOSEPH EDWARD FRANCIS, OF THORNHILL, CANADA.

CAR-COUPING.

SPECIFICATION forming part of Letters Patent No. 436,346, dated September 16, 1890.

Application filed June 5, 1890. Serial No. 354,358. (No model.)

To all whom it may concern:

Be it known that I, JOSEPH EDWARD FRANCIS, gentleman, of the village of Thornhill, in the county of York, in the Province of Ontario, 5 Canada, have invented certain new and useful Improvements in Car-Couplers; of which the following is a specification.

The object of the invention is to design an automatic car-coupler which is adapted to connect cars of both the same and different heights, and which is so formed that when the couplers are connected together they will not be liable to become separated.

Figure 1 is a perspective view of the ends 15 of two cars, which are partially broken away to exhibit my coupler. Fig. 2 is a sectional elevation.

In the drawings like letters of reference indicate corresponding parts in each figure.

20 A is the outer part or shank, and B is the inner portion of the draw-head. The inner end of the shank A is pivoted at b to the end of the inner portion B, which butts against a suitable buffer-spring C, while the outer end 25 is in elevation shaped like an arrow-head, in which the top and bottom of the head from the point to the barbs are flat surfaces c and d, the top edge of the surface c at the barb end being concaved to receive the convexed 30 bottom edge of the barb end of the surface d when the cars are coupled together.

D is a spring designed to support the shank A in position against the stop a, and E is a guiding-bracket for the shank A.

35 F is a rod extending across the bottom of the car and supported in suitable bearings f. The rod F has formed or secured on it at its center an extension-piece G, which is depressed or raised by operating the handles H on the 40 outer ends of the rod F on the outside of the car.

I are guard-rods extending from the bottom of the car—one on each side of the arrow-head-shaped end A' of the shank A—and J is a plate 45 secured on the bumper above the arrow-head-shaped end A' of the shank A.

When it is desired to couple two cars, it is merely necessary to bring them together, when the points of the arrow-head-shaped ends of 50 the shanks slide past each other, either shank of which may happen to come on top, accord-

ing to whether one car is higher than the other or the way in which they strike each other. Whichever arrow-head does come on top forces the other down, while the plate on 55 the bumper also partially receives the shock until the bottom convex-shaped barb edge of the arrow-head-shaped end of the top shank passes the top concave-shaped barb edge of the arrow-head-shaped end of the bottom 60 shank, when they drop down into position and interlock.

Both of the shanks A are held up during the period of coupling by the springs D, which give sufficiently to allow of the depression of 65 either shank A. The said springs D pass through the guiding-brackets.

When it is desired to uncouple the cars, it is merely necessary for the brakeman to tilt the handle H, so as to force the extension-piece G down against the shank A till the points of the barbs of the arrow-head-shaped 70 ends are free, when the cars may be drawn apart. The handle H being now released, the spring D forces the shank A up again into 75 its initial position.

In order to provide a means of coupling cars provided with my coupler to those couplers now in use, commonly I make a slot K through the arrow-head-shaped end A' of the shank A and 80 secure a link L in the slot K by the pin k. The link L may be drawn out till its ends strike the pin k when it is found necessary to use it for coupling.

From this description it will be seen that 85 from the peculiar construction of the arrow-head-shaped ends A' and the proximity of the guard-rods I on each side of them there will be no danger of the cars getting uncoupled while passing around a curve or in any other 90 way, except upon the derailment of the preceding car, when it would be a benefit rather than a disadvantage by having a tendency to leave the cars following on the track.

Although I show the spring D at the bottom of the shank A and a handle H for turning the rod F, it will be understood, of course, that other equivalent means might be substituted for these without altering the principle of my invention.

As my coupler is disconnected from the outside of the car, there will be no danger of

loss of life, and, being comparatively inexpensive to get up, it may be adapted with equal facility to both freight and passenger cars.

What I claim as my invention is—

- 5 1. The shank A, pivoted at b on the end of the inner part B and having an arrow head-shaped end A', formed as described, in combination with the spring D and stop a, substantially as and for the purpose specified.
- 10 2. The shank A, pivoted at b on the end of the inner part B, and an arrow-head-shaped end A', formed as described, in combination with the spring D, stop a, and extension-piece G on rod F, operated by the handle H, substantially as and for the purpose specified.
- 15 3. The shank A, pivoted at b on the end of the inner part B and having an arrow-head-shaped end A', formed as described, in combination with the spring D, stop a, extension-piece G on rod F, and plate J, secured on the

bumper, substantially as and for the purpose specified.

4. The shank A, pivoted at b on the end of the inner part B and having an arrow-head-shaped end A', formed as described, in combination with the guard-rods I, spring D, extension-piece G on rod F, and plate J, substantially as and for the purpose specified. 25

5. The shank A, pivoted at b on the end of the inner part B and having an arrow-head-shaped end A', formed as described, in combination with the link L, secured in the slot K, formed in the arrow-head-shaped end A', by the pin k, substantially as and for the purpose specified. 30

JOSEPH EDWARD FRANCIS.
